RECEPTACLE FOR VOLATILE LIQUIDS

Charles S. Packer, Chicago, Ill.

Application January 19, 1939, Serial No. 251,750

1 Claim. (Cl. 221—16)

This invention relates to improvements in receptacles adapted to contain highly volatile liquids, such as benzine, benzole, and the like, and has for its main object to provide a receptacle which is equipped with a manually operable self-closing discharge spout removable bodily from the receptacle body and which is equipped with a self-closing safety valve arranged to cause fluid escaping therethrough to be discharged from said spout.

A further object of the invention is to provide a discharge spout of the type aforesaid wherein the casing for the safety valve is so mounted upon the inner end of the discharge spout as to cause the spring for maintaining the latter normally sealed to be compressed to the degree necessary to perform its function as said casing becomes disposed in its predetermined position on said spout and wherein said last-named spring acts also to maintain normally a fluid-tight connection between said valve casing and the housing of said spout.

A suitable embodiment of the invention is illustrated in the accompanying drawing, where-

25 in:

Fig. 1 is a side elevation of a receptacle constructed in accordance with the invention.

Figs. 2 and 3 are central, longitudinal, sectional views on an enlarged scale, of the discharge spout structure and the mouth portion of the receptacle, and showing the discharge spout per se in closed and open positions, respectively.

Fig. 4 is a detail plan sectional view taken on the line 4—4 of Fig. 3.

35 Receptacles for highly volatile, inflammable liquids are subject to explosion in the event that the receptacle and contents become unduly heated. It is desirable, therefore, that the receptacle shall be equipped with a safety valve which will open automatically at a pressure far below the point at which the receptacle may be fractured.

In order to permit of manufacture of the receptacle, per se, at low cost, it is desirable that the discharge means for maintaining the receptacle normally sealed shall include the safety valve aforesaid and shall constitute a unitary structure adapted to be readily mounted upon and detached from the receptacle for permitting re-

50 fill of the latter.

In the instant case the receptacle 1 is equipped at the center of its top wall with a refill opening which is internally threaded to receive the lower externally threaded end portion 2 of a sleeve member 3 equipped between its ends with

an annular knurled flange 4. The said sleeve member 3 is equipped in its upper end portion with a bore 5 and in its lower end portion with a smaller diameter bore 6, thus providing an annular shoulder 7 between the ends of said sleeve member 3 upon which a compression spring 8 is supported.

A discharge tube 9, upon which there is rigidly mounted an outer sleeve 10 adjacent its upper end, fits telescopically within the smaller diameter bore portion 6 of the sleeve member 3 along its lower end portion and is reciprocable relatively to said sleeve member. The sleeve 10 is equipped between its ends with an annular flange 11 which is digitally engageable to force the sleeve 9 inwardly of the receptacle against the action of the spring 8. Below said flange 11 said sleeve 10 is equipped with an annularly enlarged portion 12 which fits telescopically within the larger bore portion 5 of the sleeve member 3 and is equipped at its lower end with an inwardly projecting annular flange 13 which bears upon the upper end of the sleeve 8.

The lowermost end portion of the tube 9 is externally threaded to receive the internally and externally threaded sleeve or nut 14 to which the casing 15 for the safety valve 16 is secured. Said casing 15 is equipped in its lower wall with a central opening 17 which is bordered by a seat for a gasket 18 upon which the valve 16 is held by means of a light compression spring 20 which is disposed between the lower end of said nut 14 and said valve 16.

The valve 19 is equipped with a series of peripheral projections 21 which cooperate with the inner circumferential wall of the casing 15 to maintain said valve centered within said casing and against lateral movement, the recesses between said projections 21 being adapted to permit the passage of fluid into the tube 9 when said valve 19 is unseated from the gasket 18 against the action of the said spring 20.

The said nut 14 cooperates with the lower end portion of the sleeve member 3 to maintain the spring 8 partially compressed at all times. A gasket 22 is disposed between the upper end of the nut 14 and the said lower end of the sleeve member 3 to maintain a fluid-tight joint.

In the portion of the tube 9 which is normally disposed within the smaller bore portion 6 of the sleeve member 3, there are openings 23 through which liquid is discharged when said tube 9, which constitutes the discharge spout of the device, is forced inwardly into the receptacle against action of the spring 8.

The said discharge spout structure as shown and described is very compact and easily operated and affords a seal for the receptacle to prevent the escape of any fluid from the receptacle except under the influence of pressure sufficient to open the safety valve 19, except when the said tube 9 is moved against action of the compression spring 8.

Obviously, the discharge spout structure may be disposed interchangeably upon receptacles of different sizes, this being very advantageous commercially.

I claim as my invention:

A discharge spout structure for a receptacle comprising a sleeve member adapted to be detachably mounted upon and in sealing relation to a receptacle, said sleeve member equipped with a stepped central cylindrical bore of smaller diameter at its lower than at its upper end, a tube fitting telescopically at its lower end portion in said smaller diameter bore, the upper end portion of said tube passing telescopically through and projecting from the larger diameter portion

of said bore, a compression spring in the latter engaged with said tube, a shallow cylindrical safety valve casing mounted upon and communicating with the lower end of said tube below the lower end of said sleeve member and maintained normally engaged with the latter by the action of said spring, a spring-held flat-faced and non-circular safety valve in said casing, a seat for said valve bordering an opening in the lower wall of said casing, said tube equipped with lateral openings in the portion thereof normally housed by said smaller diameter bore portion of said sleeve member to maintain said last-named openings normally sealed, and a digitally engageable member rigid with said tube for actuating the latter against the action of the first-named spring to bring said lateral openings below the lower end of the sleeve member, the outermost portions of said valve engaged with the inner cylindrical wall of the valve casing for guidance thereby.

CHARLES S. PACKER.
